[57] CLAIM

The ornamental design for a office light fixture, as shown and described.

DESCRIPTION

FIG. 1 is a front, right-side, bottom perspective view of a office light fixture showing our new design;
FIG. 2 is a top, left-side, back perspective view thereof;
FIG. 3 is a front elevational view thereof;
FIG. 4 is a top plan view thereof;
FIG. 5 is a bottom plan view thereof;
FIG. 6 is a right-side elevational view thereof, with the left-side elevational view being a mirror image thereof;
FIG. 7 is a back elevational view thereof;
FIG. 8 is a top, left-side perspective view of a second embodiment of our new design;
FIG. 9 is a right-side elevational view thereof,
FIG. 10 is a bottom plan view thereof; and
FIG. 11 is a bottom, front perspective view thereof.

FIG. 1

FIG. 2

FIG. 3

FIG. 4

FIG. 5

FIG. 6

FIG. 9

FIG. 10

FIG. 11

UNITED STATES PATENT AND TRADEMARK OFFICE
CERTIFICATE OF CORRECTION

PATENT NO. : Des. 306,909

DATED : March 27, 1990

INVENTOR(S) : Kelley et al.

It is certified that error appears in the above-identified patent and that said Letters Patent is hereby corrected as shown below:

On the title page, under DESCRIPTION:

FIG. 9, after "thereof," insert --with the left-side elevational view being a mirror image thereof;--.

Signed and Sealed this
Third Day of September, 1991
